UNITED STATES PATENT OFFICE.

RICHARD M. CRAIG, OF SAN ANTONIO, TEXAS.

DISPLAY APPARATUS.

Application filed August 19, 1925. Serial No. 51,206.

This invention relates to a novel method of and means for displaying advertising matter and the like in a manner to attract and hold the attention of the observer, the invention 5 being based on the principles of color absorption and constituting a carrying forward of the general principles disclosed in my co-pending application filed August 14, 1925, Serial No. 50,330. In the said co-pending application, the matter to be displayed is represented in one or more pigment colors upon a light or dark neutral background, as may be found desirable, and the effect of animation or change in position or condition of the matter represented is produced by successively displaying the surface bearing said matter under light rays of different spectral colors. I have discovered, however, that very pleasing effects may be obtained by using white 20 light rays in connection with light rays of a single spectral color or utilizing white light rays in connection with spectral light rays of different and contrasting colors. Therefore, the present invention has as its object to 25 evolve means whereby matter displayed in a single pigment color or contrasting pigment colors may be displayed partly by the use of white light rays to produce the effect of animation and color change and display the advertising matter in a most attractive manner.

Another object of the invention is to evolve a method whereby advertising matter in other than complementary colors, may be displayed with substantially the same facility 35 as under the method referred to in my said co-pending application in which contrasting or complementary colors are employed in representing the matter to be displayed.

In the accompanying drawings: 40 Figure 1 is a schematic view illustrating one application of the principles of the present invention, in which the matter to be displayed may be represented in contrasting pigment colors on a light neutral background and 45 displayed under white light rays and light rays of different spectral colors.

Figure 2 is a similar view showing another 50 application of the principles of the invention in which the matter to be displayed is represented in different contrasting pigment colors upon a dark background and displayed under white light rays and spectral light rays of different colors.

Figure 3 is a similar view illustrating an-

other application of the principles of the invention in which light and dark neutral backgrounds are resorted to and the matter to be displayed is represented in a single pigment color and displayed under white light rays and spectral rays of different colors. 55

Figure 4 is a similar view illustrating another application of the principles of the invention in which white light rays and spectral rays of a single color are employed in displaying the advertising or other matter which 65 is represented in a single pigment color upon a dark neutral background.

In my aforesaid co-pending application, Serial Number 50,330, and in my co-pending application filed December 29, 1925, Serial 70 Number 78,244, I have first exemplified the display of matters to be represented, under light rays of contrasting or complementary colors so that the effect of animation, color change, and daylight display may be obtained, and, in the latter application, I have exemplified the application of the general principles of the invention in a manner to continuously display certain matter to the 75 vision of the observer and display other matter at intervals with the effect of animation or change, utilizing, in the said latter instance, the principle of the blending of light rays of complementary primary colors, to produce white light. In the present application, I will exemplify the employment of 80 white light rays in combination with colored spectral rays to display matters represented in contrasting or complementary colors.

In the embodiment of the invention illustrated in Figure 1 of the drawings, the numeral 1 indicates in general the display surface, which may be a signboard or any other surface upon which advertising matter may be displayed, as well as matter intended for 85 amusement, entertainment or instruction, and there is applied to this surface a coating of a light neutral pigment which provides a light neutral background indicated by the numeral 2, upon which the matter to be displayed is represented in one or more pigment colors. By neutral colors is meant colors 90 which do not materially change under spectral color illumination, or, in other words, those colors which display no decided color 95 characteristics such as are peculiar to primary colors. It may be stated at this point that 100 in the description which is to follow, refer-

ence will also be made to pigment colors, and by this term is meant colored pigments or the colors in which the images are represented on the display surface, and reference 5 will also be made to spectral colors and by this is meant colors of the spectrum as represented by colored light rays. There are a number of light colored pigments which may be employed in painting the background of 10 the display surface illustrated in Figure 1 of the drawings, such for example as white lead or zinc white, gray, sand, etc. In the specific example represented in Figure 1, there will be painted or otherwise depicted, in red pigment 15 upon the background 2, a representation 3 of the female dressed in street costume emerging from a partly opened box, and this representation will be located at one side of the vertical middle of the display surface. 20 At the other side of the vertical middle of the display surface, there will be represented, in green pigment, advertising matter reading for example, "Doe's spring opening", as indicated by the numeral 4. This matter is intended, of course, to represent only in a general manner one of the numberless arrangements of advertising matters which may be resorted to in the carrying out of the principles of the invention, and it is within the pur- 25 view of the invention that other matters may be represented in red pigment and other matters in green pigment, the representations being alternated. Furthermore, the specific reference to red and green pigments does not 30 mean that these colors alone may be employed, inasmuch as any complementary or contrasting pigment colors may be used without in any way departing from the spirit of the invention, and, furthermore, the representa- 35 tions may be painted upon the surface of a signboard or any other surface, or they may be lithographed or photographed. In the specific embodiment of the invention illustrated in said figure, it is contemplated that 40 the display surface be illuminated successively by white light rays and light rays of contrasting or complementary colors, and while any source of illumination may be employed, it is preferable to arrange in proximity to 45 the surface, and in position to illuminate the same, a plurality of white electric light bulbs 5, red electric light bulbs 6, and green, blue-green, or blue electric light bulbs 7, the white light bulbs being so arranged that either side 50 of the display surface may be illuminated by white light rays, and the red and green bulbs being so arranged that one side of the display surface may be illuminated by red light rays and the other side by green light rays, the 55 specific arrangement being such that the red bulbs 6 will be located in juxtaposition to that side of the display surface which bears the representation 3, and the green bulbs 7 will be located in proximity to that portion of 60 the surface which bears the representation 4.

In order that the several bulbs may be properly successively lighted, a suitable flashing mechanism is provided which is illustrated diagrammatically in Figure 1 and indicated in general by the numeral 8. As an example 70 of a mechanism which may be employed, there is represented a disc 9 of insulating material in which are embedded a number of contact strips 10 and 11, the strips being ar- 75 cuate in form and being disposed concentric to the axis of rotation of the disc 9 and stag- 80 gered with relation to one another. The nu- 85 meral 12 indicates the source of current sup- 90 ply and the numeral 13 a conductor wire which is lead from one side of the source of supply to the shaft 14 upon which the disc 9 is mounted, branch wires 15 and 16 being led from the strips 10 and 11 respectively, to the said shaft. Brushes 17 and 18 are suit- 95 ably mounted in juxtaposition to the disc 85 to respectively contact the strips 10 and 11 in the rotation of the disc, and a conductor wire 19 is led from the other side of the source of current supply 12 and has branches 20 which are connected with one terminal of each of 90 the sockets into which the light bulbs 5, 6 and 7 are fitted. A conductor wire 21 is con- 95 nected to the brush 17 and the branches leading therefrom are connected to the other ter- 100 minals of the sockets for the white light bulbs 5 at the left hand side of the display surface and the other terminals of the sockets for the green light bulbs 7 at the right hand side of the display surface. A conductor wire 22 105 is led from the brush 18 and its branches are connected to the other terminals of the sockets for the red light bulbs 6 and the other terminals of the sockets for the white light bulbs 5 at the right hand side of the display surface. It will be evident that due to the 110 staggered arrangement of the contact strips 10 and 11 and the arrangement of the brushes 17 and 18, when the brush 17 is in engagement with any one of the contact strips 10, the cir- 115 110 circuit will be closed through the white or clear electric light bulbs 5 at the left hand side of the display surface and simultaneously through the green light bulbs 7 at the right hand side of the display surface, with the re- 120 sult that the representation 3 will be present- 115 ed to the view of the observer in brilliant red against a substantially white background, whereas the representation 4, which is green, will be obliterated. On the other hand, when, in the rotation of the disc 9, the succeeding 125 one of the contact strips 11 is brought into contact with the brush 18, the circuit will be closed through the red light bulbs 6 at the left hand side of the display surface and through the white light bulbs 5 at the right hand side of the said surface, so that the rep- 130 125 resentation 3 will be obliterated and the ad- 130 vertising matter constituting the represen- 130 tation 4 will be displayed to the view of the observer in green against a substantially

white background. In the method disclosed in my co-pending application, Serial Number 78,244, wherein light bulbs of contrasting colors are arranged at the opposite sides 5 of the vertical middle of the display surface, the representations are successively obliterated and displayed in black. In the present embodiment, however, due to the employment of white light bulbs in combination with 10 colored light bulbs of different colors arranged at the opposite sides of the middle of the display surface, the representations are displayed in colors, so that in the present method there is present the factor of color 15 display as well as that of animation or change in appearance of the matters to be displayed.

In the embodiment of the invention shown in Figure 2 of the drawings, quite a different effect is obtained from that described in 20 connection with the form shown in Figure 1, due to the employment of a different type of background. In this embodiment, the numeral 23 indicates in general the display surface to which there is applied a neutral pigment 25 of dark color to provide a dark neutral background indicated by the numeral 24, which background may be black, very dark gray, tobacco brown, Indian red, or any of the other dark neutral colors. Upon this 30 background, at one side of the vertical middle of the display surface, there is painted or otherwise represented, in, for example, red, a representation 25 corresponding to the representation 3 previously described, and advertising matter constituting a representation 26, in green, is painted or otherwise depicted upon the background 24 at the right hand side of the display surface. As stated in connection with the illustration disclosed in Figure 1, simple examples have been taken in 40 order to clearly represent the principles of the invention and it will be understood that much more complicated and complex arrangements of the matters to be displayed 45 may be resorted to without departing from the spirit of the invention. Likewise, in these two figures and in the other figures of the drawings, the same representations are displayed in order to more clearly exemplify 50 the different effects which may be produced by a judicious selection of backgrounds and pigment colors, as well as spectral colors. In Figure 2, sources of illumination in the nature of white light electric bulbs 27, blue light bulbs 28, and red light bulbs 29, are employed, and the white light bulbs 27 are so arranged that either side of the display surface may be 55 illuminated by white light rays, the blue light bulbs 28 being so arranged that that side of the display surface on which the representation 25 appears may be lighted in blue. The red light bulbs are so positioned as to illuminate the other side of the display surface. In this figure, the source of current supply is 60 indicated by the numeral 30 and the flasher, 65 which is indicated in general by the numeral 31, corresponds in every respect to the flasher 8 in Figure 1 of the drawings, a conductor wire 32 being led from one side of the source of current supply to the shaft 33 of the flasher disc 34 and by way of branch wires 35 and 36 to contact strips 37 and 38 respectively. Brushes 39 and 40 are provided in connection with the flasher disc and coact respectively 70 with the contact strips 37 and 38. A conductor wire 41 leads from the brush 39 and is connected electrically with one terminal of the socket for each of the white light bulbs 27 at the left hand side of the display surface and with one terminal of the sockets for the red light bulbs 29 at the right hand side of the 75 said display surface, a conductor wire 42 being led from the brush 40 and being connected to one terminal of the sockets for the blue light bulbs 28 and to one terminal of the 80 sockets for the white light bulbs 27 at the right hand side of the display surface. A conductor wire 43 leads from the other side of the source of current supply and is connected to the other terminals of the sockets for the light bulbs 27, 28 and 29. In this 85 embodiment of the invention, when the white light bulbs at the left hand side of the display surface are lighted and the red bulbs at the right hand side of the display surface 90 are simultaneously lighted, the red representation 25 will appear bright red against the dark neutral background and the representation 26 will be obliterated. On the other hand, when the blue light bulbs 28 are lighted 95 and illuminate the left hand side of the display surface and the white light bulbs 27 at the right hand side of the display surface are simultaneously illuminated, the representation 25 will be obliterated and the representation 26 will appear bright green against the dark neutral background 24. 100

Figure 3 of the drawings illustrates another application of the principles of the invention and in this figure the numeral 44 indicates in general the display surface, one half of which has applied to it a dark neutral pigment to provide a dark neutral background 45 which may, for example, be brown in color. A light neutral pigment is applied 105 to the other half of the display surface and provides a light neutral background indicated by the numeral 46. Upon the background 45 there is painted or otherwise depicted, in red, the representation 47 corresponding to the representations 3 and 25 previously referred to, and advertising matter constituting another representation 48 is represented in red upon the background 46. White light bulbs 49 are arranged in juxtaposition to the display surface so that either 110 half thereof may be illuminated with white light rays, and blue light bulbs 50 and red light bulbs 51 are respectively arranged in 115 juxtaposition to the display surface so that 120

125

130

the portion thereof bearing the representation 47 may be illuminated by blue light rays and the portion thereof bearing the representation 48 may be illuminated by red light rays.

6 The numeral 52 indicates a source of current supply and the numeral 53 indicates in general a flasher identical with that described in connection with Figures 1 and 2 and arranged to control the supply of current to the light bulbs 49, 50 and 51, the circuit being identical with the circuit disclosed in Figures 1 and 2, and being so arranged that at one moment the white light bulbs 49 at the left hand side of the display surface will be lighted and simultaneously the red light bulbs 51 at the other side of the said surface will be illuminated, and at the next moment, the blue light bulbs 50 and the white light bulbs 49 at the right hand side of the display surface will be simultaneously illuminated. When the white light bulbs 49 at the left hand side of the display surface are illuminated and simultaneously the red light bulbs 51 at the right hand side of the said surface are illuminated, the representation 47 will appear bright red against a dark background and the representation 48 will be obliterated. On the other hand, when the blue light bulbs 50 are lighted and the white light bulbs 49 at the right hand side of the display surface are simultaneously lighted, the representation 47 will be obliterated and the representation 48 will appear red against a white background.

In the embodiment of the invention illustrated in Figure 4 of the drawings, the display surface is indicated in general by the numeral 54 and a dark neutral pigment, as for example brown, is applied to the surface to provide a dark neutral background 55.

40 Upon this surface, at one side of the vertical middle thereof, there is painted or otherwise represented in red, a representation 56 which corresponds to the representations 3, 25, and 47, previously referred to, and, at the opposite side of the background there is painted or otherwise depicted, in red, a representation 57 corresponding to the representation 48. This embodiment differs from the embodiment shown in Figure 3 in that the entire display surface is provided with a dark neutral background instead of with a combination of dark and light neutral backgrounds. The display surface 54 is to be illuminated by white light bulbs 58 and by blue light bulbs 59, and the supply of current from the source of supply 60, to the said bulbs, is selectively controlled through the medium of a flasher indicated in general by the numeral 61 and identical with the flashers 8, 31 and 53 previously described. Identically the same circuit is employed in this instance as in the preceding instances and, as a consequence, when the white light bulbs 58 at the left hand side of the display surface are lighted, the blue light bulbs 59 at the right hand side of the display

surface will be simultaneously lighted and, on the other hand, when the blue light bulbs at the left hand side of the display surface are lighted, the white light bulbs at the right hand side of the display surface will be simultaneously lighted. Therefore, when the white light bulbs 58 at the left hand side of the display surface are lighted and the blue light bulbs 59 at the right hand side are simultaneously lighted, the representation 56 will appear bright red against a dark background but the representation 57 will be obliterated and, conversely, when the blue light bulbs 59 at the left hand side of the display surface are lighted and the white light bulbs 58 at the right hand side are lighted simultaneously therewith, the representation 56 will be obliterated and the representation 57 will appear red against a dark background.

It will be understood, as previously stated, that more complex arrangements may be devised than illustrated in the drawings and hereinbefore described, and colors other than those enumerated may be employed, both as regards the pigments used in depicting the representations, and the spectral light rays under which the display surface is illuminated.

It will be observed from the foregoing that the display surfaces herein illustrated and described will possess full daylight value as well as providing a brilliant display at night.

In the several embodiments of the invention illustrated and described, the principles have been adapted primarily to advertising displays, but it will be evident that this disclosure is not to be construed as in any way limiting the invention inasmuch as the principles thereof may be employed in color displays for any purpose whatsoever, such for example as scenic effects, amusement displays, cabarets, walls, educational displays, etc., and, therefore, where reference is made to a "display surface" this term is to be considered as descriptive of any surface having the general characteristics set forth herein and displayed in accordance with the principles of the invention.

Having thus described the invention, what I claim is:

1. Display apparatus comprising a display surface having a dark neutral background bearing upon different portions different matters to be displayed represented in contrasting pigment colors and each disclosed when exposed to a white light, and means for simultaneously, alternately, and successively subjecting said background and matters to white light rays and light rays of contrasting spectral colors substantially complementary to the respective pigment colors in which the matters are represented whereby the matters will be alternately displayed and one hidden from view by the cooperating spectral color during display of the other.

2. Display apparatus comprising a display surface having a neutral surface background bearing upon different distinct portions thereof, different matters to be displayed, 5 represented in contrasting pigment colors, and means for simultaneously, alternately, and successively displaying said surface

background in the presence of white light rays and light rays of contrasting spectral colors substantially complementary to the respective pigment colors in which the matters are represented. 10

In testimony whereof I affix my signature.
RICHARD M. CRAIG. [L.S.]
